(57) **CLAIM**

The ornamental design for a grip with an oval base as shown and described.

DESCRIPTION

FIG. 1 is a front perspective view of the grip with an oval base with a grip member in an extended position;
FIG. 2 is a back perspective view thereof;
FIG. 3 is a front view thereof;
FIG. 4 is a back view thereof;
FIG. 5 is a right side view thereof;
FIG. 6 is a left side view thereof;
FIG. 7 is a top view thereof;
FIG. 8 is a bottom view thereof; and,
FIG. 9 is another front perspective view thereof with the grip member collapsed.
Broken lines illustrate portions of the grip with an oval base that form no part of the claimed design.
